UNITED STATES PATENT OFFICE

LOUIS KOLKER, OF FAR ROCKAWAY, NEW YORK

DESIGN FOR A CHAIR OR SIMILAR ARTICLE

Application filed July 18, 1930. Serial No. 36,390. Term of patent 7 years.

To all whom it may concern:

Be it known that I, LOUIS KOLKER, a citizen of the United States of America, residing at Far Rockaway, Queens County, State of New York, have invented a new, original, and ornamental Design for a Chair or Similar Article, of which the following is a specification, reference being had to the accompanying drawing, forming part hereof, in which—

I claim:

The ornamental design for a chair or similar article as shown.

Signed at New York city, this 14th day of July, 1930.

LOUIS KOLKER.
